UNITED STATES PATENT OFFICE.

LEONARD A. GUMPORT, OF NEW YORK, N. Y.

BUCKLE FOR ADJUSTABLE NECKTIES.

Application filed September 19, 1927. Serial No. 220,529.

This invention relates to an adjustable tie and has for one of its objects the provision of a buckle for securing sections of a tie together.

5 Another object of my invention is the provision of a buckle for adjustable ties having a longitudinally curved body portion and comprising end extensions which are adapted to support the body portion in spaced relation to a collar band to permit free and easy passage of the buckle by a back collar button.

A further object of my invention is the provision of an adjustable tie comprising a 15 buckle which may be suitably adapted for accommodating ties comprising material of different thicknesses.

Other objects will appear hereinafter, the novel features and combinations being more 20 clearly set forth in the appended claims.

In the drawings:

Fig. 1 is a top plan view of a tie embodying my invention.

Fig. 2 is a bottom plan view of a tie embodying my invention.

Fig. 3 is a perspective view of an element of the buckle embodied in my invention.

Fig. 4 is a perspective view of another element of the buckle embodied in my invention.

Fig. 5 is an end view of an assembled buckle.

Fig. 6 is a transverse sectional view taken on the line 6—6 of Fig. 5.

Fig. 7 is a fragmentary sectional view of a buckle illustrating a modified attachment of a tie section thereto.

Fig. 8 is a sectional view of a further development of my invention.

40 Referring particularly to the drawings the numeral 10 designates one tie section and the numeral 11 another. The left end of the tie section 11 is looped as at 12 and is stitched as at 13. A ring member 14 preferably comprising wire is disposed through the loop 12.

The extremity of the tie section 10 is threaded through the ring 14 and is secured to a buckle hereinafter more clearly described.

55 The buckle comprises a body portion 15 having end flanges 16 and 17 thereon and a lever member 18. The lever member 18 comprises a metal plate formed with an angularly disposed forward section 19. As illus-

trated in Figs. 5 and 6 the body portion 15 has a longitudinal and lateral curvature and the edge 20 of the forward section 19 is also of arcuate curvature. The lever member 18 is provided with end extensions 21 and 22 which are adapted to be journaled in apertures 23 and 24, respectively. The lever element 18 is provided with a slot for receiving the extremity of the tie section 10 which is threaded therethrough and looped as at 26 60 the looping being secured by stitches 27. It should be understood that the intermediate portion of the tie section 11 is threaded through the buckle between the inner surface of the body portion 15 and the edge 20 of the 65 forward section 19.

As illustrated in Fig. 5 the flanges 16 and 17 of the body portion 15 extend in advance of the lever member 18 and are adapted to retain the same in spaced relation to a collar 70 band for providing a space between the buckle and the band to permit passage of the buckle over a back collar button, it being understood that the buckle may be disposed in straddled relation to a button, not shown 75 in the drawings. The above described construction provides an adjustable tie which may be freely moved longitudinally on the neck of a wearer. It is pointed out that the lever 19 has a smooth and unobstructed 80 outer concaved surface between the flanges 16 and 17, disposed inwards from the outer free ends of the flanges forming an unobstructed passage so that a collar button straddled by the flanges 16 and 17 may not 85 hinder the passage of the buckle thereover.

It should be understood that the intermediate portions of both sections 10 and 11 may be of single layer thickness and that with my improved device the lining member 90 customarily used in tie construction is unnecessary and eliminated. Numerals indicating various sizes are printed on the bottom side of section 10 and are adapted to aid in predetermining the length of the tie. 95

The edge 20 of the forward section 19 is convex and is of a curvature similar to the concave curvature of the body portion 15. When the lever member 18 is in its upward position shown in Fig. 6, the edge of the forward section 19 thereof is positioned in close proximity to the inner surface of the body portion 15 and the tie material disposed therebetween is firmly clamped. The lever member may be rotated to the dotted line 100 105 110

position shown in Fig. 6 for releasing the tie section. It should be understood that the buckle comprises material of sufficient resiliency to permit the forward section 19 of the lever to be rotated past the vertical position wherein rotation is resisted by the body member 15. This arrangement prevents accidental rotation of the lever to open or unclamped position because of the force required to move the forward section past its vertical position.

It should be also understood that when the lever 18 is in its uppermost position the edge of the body member 15 may extend into the slot 25 in the lever as illustrated in Fig. 6. It should also be understood the device herein described may be employed on other wearing apparel such as suspenders, garters, etc., not shown in the accompanying drawing.

20 In Fig. 7 of the drawings the extremity of the tie section 10 is folded and stitched at 29 to provide an enlargement which is of greater dimensions than the slot 26.

In the modified form of my invention illustrated in Fig. 8 the body member 15' comprises end flanges 16' which are provided with a vertical slot 30. Irregular notches 31 are communicative with the slot 30 and are adapted to receive the projections 21 and 30 22 of the lever member 18 above described. It should be understood that the above described construction is such as will permit the lever member 18 to be adjustably mounted on the body member 15' so as to 35 predetermine the distance between the edge 20 of the lever and the inner surface of the

body member 15' to accommodate ties comprising materials of different thicknesses.

Obviously those skilled in the art may make various changes in the arrangement 40 and parts of my invention without departing from the spirit and scope thereof.

Having thus described my invention what I claim as new and desire to secure by United States Letters Patent is:

45 1. A buckle for adjustable neckties, comprising a frame having end flanges directable towards a collar band to hold the buckle in spaced relation to the collar band, and a clamping lever, pivotally mounted in the end flanges, and having an outer concaved surface disposed inwards from the outer free ends of the flanges forming a smooth and unobstructive passage providing for the free and unobstructed passage of a collar 55 button beneath the concaved surface and between the end flanges.

2. A buckle for adjustable neckties, comprising a frame having end flanges directable towards a collar band to hold the buckle 60 in spaced relation to the collar band, said end flanges being provided with slots communicating with irregular notches, and a clamping lever, pivotally mounted in the slots and notches, and having an outer concaved surface, providing for the free and unobstructed passage of a collar button beneath 65 the concaved surface and between the end flanges.

In testimony whereof I have affixed my 70 signature.

LEONARD A. GUMPORT.
